UNITED STATES PATENT OFFICE.

CONRAD DRESSLER, OF MARLOW, ENGLAND.

TUNNEL-OVEN.

1,285,647.

Specification of Letters Patent. Patented Nov. 26, 1918.

Application filed July 28, 1917. Serial No. 183,318.

To all whom it may concern:

Be it known that I, CONRAD DRESSLER, a subject of the King of Great Britain and Ireland, residing at Marlow, in the county of Buckingham, England, have invented Improvements in or Relating to Tunnel-Ovens, of which the following is a specification.

In tunnel ovens of the kind in which gaseous liquid or like fuel (hereinafter referred to generally as gas) is burnt in independent combustion chambers arranged longitudinally of the oven, as described in the specifications of former Letters Patent granted to me, No. 1023628, dated April 16th, 1912, No. 1116036, dated November 3rd, 1910, and No. 1170428, dated February 1st, 1916, it has been customary to introduce the gas and air practically at one point only in the length of each combustion chamber so that the hottest part of the oven occupies only a short portion of the length of the oven, located usually near the center of the length of the oven. As a result, the goods, which travel slowly and continuously through the oven, are subject to the maximum temperature for only a comparatively short time. It is however desirable in some cases, as for instance when firing massive pieces of sanitary ware or other goods requiring very high temperatures or good heat distribution therein, that the goods shall be exposed to the maximum temperature, or to a high temperature which may be between the maximum and minimum temperatures of the oven, for a prolonged period, or that they shall be subjected alternately to a high temperature, then to a lower temperature and then to a high temperature in succession, or to a repetition of high, lower and high temperatures, so that they shall undergo a heat soaking treatment instead of being gradually heated up to the maximum temperature and then gradually cooled without being subjected to any prolonged heating at the maximum or at any one temperature.

In tunnel ovens as described in, further Letters Patent granted to me, No. 1,225,318, provision is made for regulatably introducing gas and air at different points along the length of the combustion chamber, with the object of producing temperature regions differing between themselves but each more or less uniform throughout a predetermined length of the combustion chamber, the heat derived from a given burner being supple-

mented by that produced by another or other burner or burners rearward thereof. The mingling of the products of combustion from forward burners with the newly entering gas and air at that or those in rear thereof by diluting the latter prevents the temperature of combustion rising to as high a point as it otherwise might, successive burners accordingly losing in effectiveness correspondingly with the extent of dilution of their gas and air by the inert products of combustion from burners forward thereof.

Now the present invention has for its object to construct and operate tunnel ovens having longitudinally arranged combustion chambers as referred to, with successive inlets for gas and air rearward one of another whereby more effective combustion is obtained at the successive burners, better regulation secured of the temperature of any given zone and attainment of a higher temperature in a maximum temperature zone rendered practicable. The combustions are so regulated that a curve representing the temperature at various parts along the oven shall have a prolonged raised portion more nearly approaching a straight line than is attainable with the said referred to tunnel ovens.

By such means goods while traveling continuously through the oven can be subjected for a prolonged period to a substantially uniform high temperature that may be the maximum temperature of the oven, or involve zones of substantially uniform maximum temperature separated by one or more like zones of lower but still high temperature.

For this purpose according to the present invention each combustion chamber is provided at separated points along its length with two or more combustion zones each comprising a combustion space with inlets for gas and air and hereinafter referred to collectively, for brevity, as a burner in such manner that the combustion spaces or zones in the longitudinally extending combustion chamber shall be independent of each other so that the gas supplied to each of them can be burnt by pure air and therefore under the most favorable and efficient conditions. This system of working yields short flames or zones of heat of high intensity instead of long flames of lower intensity obtained with the former system of working. Both systems however enable soaking zones to be

obtained suitable for different classes of work. To enable this result to be obtained the combustion chambers may be so constructed that the products of combustion from the rear burner can be led away without coming into contact with the air and gas supplied to the forward burner so that the combustion of the gas delivered to the forward burner can be effected independently of that delivered to the rear burner. In this way the maximum temperature of combustion can be obtained rapidly and in an advantageous manner at each burner so as to produce two zones of heat of maximum temperature spaced at any desired distance apart. By placing the burners not far apart, the two zones will form substantially one zone of a nearly uniformly high temperature. By placing them farther apart the two zones of maximum temperature will be separated by a zone of heat of lower but still high temperature. In this way the goods during their travel through the oven can be subjected to a prolonged heat soaking treatment. As will be obvious more than two independent burners may be provided to obtain any desired heating effect.

The longitudinal combustion chambers can be variously constructed to provide independent burners for the combustion of the gas supplied thereto for the purpose of the invention.

In order to utilize the heat of the hot products of combustion, from the rear burner, such products may, with advantage, be led forward to a point in advance of the forward burner and be ultimately mixed with the products of combustion coming from that burner and the heat of the mixed products utilized for heating goods in the forward part of the oven. For this purpose a by-pass is necessary which may be arranged inside or outside the combustion chamber.

In the accompanying illustrative drawings, Figure 1 shows in horizontal section on the line A A of Fig. 2 and more or less diagrammatically, a portion of a tunnel oven, of the kind referred to, with one construction of combustion chamber according to the invention and Figs. 2 and 3 are cross sections thereof on the lines B B and C C respectively of Fig. 1. Figs. 4 and 5 are diagrammatic views showing modified constructions. Figs. 6 and 7 are respectively a vertical section on the line D D of Fig. 7 and a horizontal section on the line E E of Fig. 6 showing another modified construction. Fig. 8 is a cross section on the line F F of Fig. 6. Figs. 9, 10 and 11 are horizontal sections and Figs. 12, 13 and 14 are vertical sections, showing diagrammatically, further modified constructions.

In the construction of combustion chamber shown in Figs. 1, 2 and 3, in which an inter-

nal by-pass is provided, the interior of each longitudinal combustion chamber *a* is divided longitudinally for part of its length by a vertical longitudinal partition *b* into two compartments *c* and *c'* of more or less equal cross sectional area and each provided with an inlet *d* or *d'* for gas and an inlet *e* or *e'* for air. The inlets *d* and *d'* for gas are, as shown, arranged at a distance apart longitudinally of the oven to constitute forward and rear burners respectively. The inlets *e* and *e'* for air, may, as shown, be arranged near together at the rear of the rear gas inlet *d'* and be separated from each other by a longitudinal partition *b'* or not. Or a single air inlet at the rear of the rear gas inlet *d'* may be provided and the partition *b'* omitted as shown in Fig. 4. Usually however it will be advantageous to provide separate air inlets as shown in Fig. 1.

The gas and air inlets are controlled by separate dampers *f* and *g* respectively, or equivalent controlling means. The products of combustion are caused to flow through the separate compartments *c* and *c'* under the action of the fan or chimney with which the outlet ends of the combustion chambers are ordinarily connected as usual. At one end, the two longitudinal compartments may, as shown, merge into an undivided end portion *c'* of the combustion chamber. The gas and air inlets *d*, *d'* and *e*, *e'* may, as shown, be arranged at the bottom and top respectively of the combustion chamber and the part *h* of the length of the chamber containing each gas inlet *d*, *d'* and constituting a fire box, may, as in the example shown, be made separate from the rest of the chamber and be connected thereto, the arrangement being such as to allow for expansion and contraction of the parts *h* of the combustion chamber. The whole combustion chamber, may, as heretofore, bear upon a sand covered base as described in my prior patent No. 1,023,628, to allow for its free expansion and contraction and be provided at its cooler or inspection end with an expansion sleeve *i*. It is preferred that the longitudinal compartment *c* containing the forward gas inlet or burner *d* shall be next the passageway for goods traveling through the oven and the other compartment *c'* next to the adjacent side of the oven wall *G*.

By the arrangement described the air supplied to the forward burner *d* will be heated to a high temperature while flowing through the rear portion of its longitudinal compartment *c* adjacent to the other longitudinal compartment *c'* corresponding to the rear burner *d'* whereby very efficient combustion of the gas at the forward burner *d* and the production of a high temperature can be effected in an economical manner. Also, the products of combustion from both burners are afterward merged together in the undivided end portion *c'* of the combustion chamber.

vided portion a^1 of the combustion chamber and their remaining heat utilized while in that chamber and in any heating tubes that may be connected thereto and with the chimney or suction fan, according to the design of oven to which the invention is applied.

The longitudinal partition b in the combustion chamber may be made in superposed sections placed end to end and of refractory material that may advantageously be carbon or like material, the superposed sections being flanged where necessary, as shown at b^2 in Fig. 3, to provide sufficient strength. The joint at j between the top of the partition b and the top a^2 of the combustion chamber (see Fig. 3) may advantageously be made with sandy clay which will readily yield to allow for movement due to expansion between the parts. The partition b and its connection with the combustion chamber may not at all times be perfectly air tight but this will not seriously affect the desired operation of the burners.

According to the modified constructions, shown in Fig. 5, the longitudinal partition b may extend forward only from the gas inlet d of the forward burner and at this point be combined with a transverse partition b^3 to form a longitudinal compartment c closed at the rear end where it will also be provided with an air inlet e at the top.

Instead of using a longitudinal vertical partition b as shown in Figs. 1, 2 and 3, one or more partitions may also be arranged horizontally, if desired, the gas and air inlets being suitably arranged to meet the altered positions of the compartments.

Figs. 6, 7 and 8 show a construction of combustion chamber of this kind provided with a number of separate burners or combustion zones r arranged in tandem with the top walls s thereof arranged horizontally at different levels, stepwise, and at one side of a longitudinal vertical partition t . Each burner or combustion zone r has at one end, an inlet d , at the bottom, for gas, and above it an end inlet e for air from a hot air supply compartment u arranged at one side of the partition t . At the other end, each burner or combustion zone r is in communication through a lateral outlet v with a compartment w arranged at the other side of the partition t and which serves to receive the hot products of combustion from all the burners or combustion zones and deliver them into the forward portion a^1 of the combustion chamber a or flue.

In the modified construction shown in Fig. 9, each combustion chamber a is provided at the part thereof where the forward burner d is located, with a centrally arranged tube or conduit h of refractory material through which the products of combustion from the rear burner d^1 can flow past the combustion zone of the forward burner and mingle with

the products of combustion from that burner at an advanced part a^1 of the chamber.

Or, as shown in Fig. 10, a tube or conduit m may be arranged to extend into and partly through the combustion chamber a to supply air to the gas inlet d of the forward burner and protect the resulting flame from the products of combustion flowing over, around or past it from the rear burner d^1 .

In the further modified construction shown in Fig. 11, the combustion chamber a is provided, adjacent to and behind the forward burner d , with a transverse wall n dividing it into two main longitudinal parts a^3 and a^4 and with an external by-pass flue or passage a^5 that connects the rearward portion a^4 to the forward portion a^3 at a point a^6 where the products of combustion from the rear burner d^1 will not affect the combustion of the gas at the forward burner d . The by-pass flue or passage a^5 may be arranged in different ways; in the example shown in Fig. 11, it is arranged at the outer side of the combustion chamber and extends into the adjacent side wall G of the oven.

In the arrangements hereinbefore described where the combustion of gas by air at the forward burner is unaffected by products of combustion coming from the rear burner, the maximum heat under the condition of supply of air and gas obtaining, will be attained at each burner, and a prolonged heating zone of a more or less substantially uniformly high temperature for the goods to travel through, will, notwithstanding that the burners are displaced longitudinally, be obtained by reason of the hot air which, as shown by the arrows in Fig. 3, is caused to flow, by convection, under, around and over the combustion chamber and downward through the heating zone F between the combustion chambers through which the goods are traveling, as described in the said former specifications.

It will be understood that in some cases the burners may be arranged in series so that the products of combustion mixed more or less with air, coming from the rear burner, will pass through the combustion space of the forward burner to which air and gas are separately delivered. In this system of working instead of obtaining short flames or zones of heat of high intensity, as with the system of working hereinbefore described, long flames of lower intensity will be obtained. This system of working will not be so economical in fuel, or be so easily controlled, as the first system described. Both systems will however enable soaking zones to be obtained suitable for different classes of work. Fig. 12 shows, in vertical section, one arrangement designed to work on the second system referred to, d and e being the gas and air inlets of the forward burner and

d^1, e^1 those of the rear burner, the combustion spaces of both being in free communication with each other.

Fig. 13 shows a modified arrangement 5 wherein the gas is supplied through a pipe D having a number of burner outlets $d, d^1, d^2 \dots d^4$ spaced apart longitudinally and to all of which air is supplied from one end 10 of the combustion chamber a, it may be from a pipe e, or otherwise, the products of combustion from all the burner flames flowing forward together into the forward portion a^1 of the combustion chamber.

Fig. 14 shows a modification of Fig. 13, 15 wherein the air is supplied through a pipe e having a number of outlets $e, e^1 \dots e^4$ and the gas is supplied through an inlet d to be burnt by the air issuing from each of the air outlets.

20 As will be obvious the details of construction can be variously modified.

What I claim is:—

1. In a tunnel oven, a longitudinally arranged combustion chamber having a plurality of combustion zones at different parts 25 of its length, said combustion zones being independent of each other so that products of combustion from one cannot flow through another.

30 2. In a tunnel oven, a longitudinally arranged combustion chamber having a plurality of burners disposed at points along its length and arranged so that combustion is effective in zones independent of each 35 other, the products of combustion from the said zones afterward discharging into a portion of the chamber common to them and serving as a flue.

3. In a tunnel oven, a longitudinally arranged combustion chamber having a plurality of independent combustion zones arranged at different points along its length and a conduit through which products of combustion from a rear combustion zone 45 can flow past a forward combustion zone without entering it.

4. In a tunnel oven, a longitudinally arranged combustion chamber having a plurality of combustion zones arranged at different points along its length and partitioning means arranged within said chamber so as to prevent products of combustion from one combustion zone passing through a forward combustion zone.

55 5. In a tunnel oven, a longitudinally arranged combustion chamber having a plurality of combustion zones spaced apart

along its length, the flue of one zone extending along that of a forward combustion zone, the discharging ends of the zones 60 communicating with a flue common to them.

6. In a tunnel oven, a longitudinally arranged combustion chamber having a plurality of combustion zones at different parts of its length and longitudinally arranged partitioning means separating said combustion zones from each other.

7. In a tunnel oven, a longitudinally arranged combustion chamber having inlets for combustible gas at different points of 70 its length and partitioning means arranged within said chamber and arranged to form separate compartments each provided with one of said combustible gas inlets, and each having an inlet for air.

8. In a tunnel oven, a longitudinally arranged combustion chamber having inlets for combustible gas at different points of 75 its length and also means for admission of air, and longitudinally arranged partitioning means arranged within said combustion chamber to form separate compartments each provided with one of said inlets for gas and each in communication at one end with a part of the chamber provided with said air admission means and at the other end with a part of the chamber 80 serving as a flue common to the compartments.

9. In a tunnel oven, a longitudinally arranged combustion chamber, a partition arranged longitudinally within said chamber for part of its length so as to form therewith two longitudinal compartments each in communication at its ends with portions 95 of the chamber common to both compartments, each compartment having an inlet for combustible gas and an inlet for air, the gas inlets being arranged at different points along the length of the chamber.

10. In a tunnel oven, a longitudinally arranged combustion chamber having a longitudinally arranged vertical partition extending along a part thereof and dividing it into two parallel compartments communicating at their outlet ends with a part of the chamber common to them, each compartment having an inlet for gas and an inlet for air, the gas inlets for the two compartments being displaced longitudinally 105 of the chamber.

Signed at London, England, this eleventh day of July, 1917.

CONRAD DRESSLER
